CHILD'S SLIPPER HOLDER

Alma H. Douglas and Le Roy M. Douglas,
San Francisco, Calif.

Application October 15, 1949, Serial No. 5,498

Term of patent 14 years

(Cl. D58—2)

To all whom it may concern:

Be it known that we, Alma H. Douglas and Le Roy M. Douglas, citizens of the United States, residing in the city and county of San Francisco and State of California, have invented a new, original, and ornamental Design for a Child's Slipper Holder, of which the following is a specification, reference being had to the accompanying drawing, forming a part hereof.

In the drawing:

Fig. 1 is a front elevation of a child's slipper holder, showing our new design;

Fig. 2 is a rear elevation of the same;

Fig. 3 is a top plan view of the same; and

Fig. 4 is a side elevation of the same.

We claim:

The ornamental design for a child's slipper holder, substantially as shown.

ALMA H. DOUGLAS.
LE ROY M. DOUGLAS.
